UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

MACHINE FOR USE IN THE MANUFACTURE OF BOOTS AND SHOES.

1,115,484.

Specification of Letters Patent.

Patented Nov. 3, 1914.

Application filed July 15, 1908. Serial No. 443,666.

To all whom it may concern:

Be it known that I, ARTHUR BATES, a subject of the King of England, residing at Leicester, in the county of Leicester, England, have invented certain Improvements in Machines for Use in the Manufacture of Boots and Shoes, of which the following description, in connection with the accompanying drawings, is a specification, like reference characters on the drawings indicating like parts in the several figures.

This invention relates to machines for operating upon boots and shoes, and particularly to machines that operate upon the heel portions thereof, such, for example, as machines for inserting fastenings or the like in the heel seat of the shoe sole, or in the tread face of the heel, or machines for performing other operations upon the heel portions of boots and shoes.

An important feature of the present invention comprises the provision in machines of the class above referred to, which have a work holder and a tool for operating upon the heel portion of a shoe, of automatic mechanism which effects relative movement between the work holder and tool in a predetermined path. Preferably the automatic mechanism just referred to is constructed and arranged to effect a relative movement of the work holder and tool in a path corresponding with the contour of the heel portion of the shoe and is preferably adjustable to vary the path of such relative movement to adapt the machine for operating upon heel portions of different sizes or shapes. Some of the advantages accruing from the employment of such automatic mechanism are that the operator is relieved from the necessity of moving or guiding the work or tool during the operation of the machine, and that greater uniformity is obtained in the treatment of a number of shoes of the same size than is the case when the shoes are guided by hand.

A further important feature of the invention is the provision of automatic mechanism for effecting a relative movement of a work holder and tool in a machine of the class above referred to which operates in

such manner that the lateral surfaces as well as the surface being operated upon are maintained in substantial parallelism throughout the relative movement or at least that the same face of the work is presented to the operator throughout the relative movement of the work holder and tool. A convenient embodiment of this feature of the invention comprises a construction in which the work feeding means is constructed and arranged to carry the work bodily into each of the successive operative relations of the work and tool. An advantage of this feature of the construction is that it simplifies the manipulation of the shoe on the part of the operator.

Another feature of the invention that is particularly applicable to a machine in which the tool, for example a fastening driving mechanism, acts intermittently upon the work, is the employment of automatic locking means that prevents accidental relative movement between the work holder and tool while the latter is operating upon the work.

The invention comprises further the provision of means which acts at the completion of the operation of the machine upon one shoe to "set" the automatic mechanism aforesaid in such manner that during the operation upon the next shoe the relative movement of the tool and work holder, although following the same path as before, will be in the reverse direction, and an important feature of the invention is the provision in a machine for inserting fastenings of automatic work feeding means operating to feed the work alternately in different directions. An advantage of a construction of this type is that by it an operator may more conveniently place upon the two shoes of a pair the differing characteristics in the way of fastening designs. This arrangement of the automatic mechanism for effecting the relative movement has an especial advantage in the illustrated construction in that it effects a considerable saving of time in the treatment of a number of shoes, since by it the said mechanism, after the operation upon one shoe is completed, does not have to

be returned to an initial position but is automatically put into readiness for dealing with another shoe.

Other features of the invention comprise 5 the provision in a mechanism for automatically effecting a relative movement of a work holder and a tool along a predetermined path, of means for centering the work in the work holder to bring it into such relation to the movements of the mechanism 10 that the operations of the tool upon it will bear a proper relation to it, and the provision of automatic mechanism for effecting the relative movement above referred to 15 which can conveniently be placed out of operative relation to the tool whereby the tool may be used independently of said mechanism.

The automatic mechanism may comprise 20 a crank or its equivalent driven by connections from any suitable moving part of the machine, and coupled to a holder for the tool or for the work, and a guiding device for the holder, for example a pin engaging 25 a straight slot formed in the holder. Oscillation of the crank about its center will impart to the holder a movement that is a combination of a circular movement derived from the crank and a right line movement 30 caused by the constraining action of the guiding device upon the holder. A point on the holder can readily be located that describes a curve corresponding substantially to that of the contour of the edge of a 35 heel seat of a shoe sole or of the edge of the tread face of the heel. This mechanism may be so combined with a tool and a work 40 holder that one of the latter two elements may be arranged to be moved by it relatively to the other, and thus the tool be caused to operate upon the work carried in the work holder in a line corresponding to the contour of the heel portion.

The point of connection between the crank 45 and the holder is preferably adjustable toward and from the fulcrum of the crank, thereby to vary the effective length of the crank and alter the size of the curve traced by the point aforesaid on the holder to suit 50 heels or heel seats of different size. As different points on the holder describe curves varying in size, an adjustment for heels or heel seats of different sizes could be obtained by shifting the location of the work or of 55 the tool with respect to the path of movement of the holder of the automatic mechanism. In the event of such adjustment of the movable member, causing the companion member to be displaced with relation to 60 its companion, means may be provided for readjusting the parts to bring them again into their proper cooperative relationship.

In the construction embodying the present

invention hereinafter described, an element 65 of the guiding device, namely the pin and slot connection hereinbefore referred to, is mounted upon a crank for its support and is adjustable toward and from the fulcrum of said crank. This crank is oscillated preferably in the same sense as the crank first 70 mentioned, by connections from any moving part of the machine; for instance, it may be geared to its companion crank.

The machine hereinafter described, in addition to operating upon the heel portion, is 75 adapted to operate upon other parts of the boot or shoe, and accordingly it is desirable that the automatic mechanism aforesaid be arranged to be readily thrown out of operation. To this end the crank or cranks 80 aforesaid and the work holder are all mounted upon a member that can be moved to place them clear of the other working parts of the machine, and means is preferably provided for locking the member in 85 positions which correspond with the operative and inoperative positions of the said automatic mechanism.

A convenient embodiment of the present 90 invention will now be described by way of example as applied to a machine that is employed for driving tacks to secure the outer soles to the inner soles of boots and shoes, in which machine a tack strip has tapered tacks 95 cut from it which are driven into the work by a driver.

In the accompanying drawings,—Figure 1 is a side elevation of so much of the machine just referred to as is necessary to illustrate the application of this invention 100 thereto; Fig. 2 is a plan view of the work feeding and guiding mechanism shown in Fig. 1 and which comprises one embodiment of the invention; Fig. 3 is a detail view of the pawl and ratchet means for actuating 105 the work feeding mechanism; Figs. 4, 5 and 6 are detail views of the locking mechanism for preventing movement of the work feeding mechanism when the fastening is being driven, and Fig. 7 is a plan view of means 110 for moving the work feeding mechanism into and out of operative relation to the fastening inserting mechanism.

It will be understood by those skilled in the art that fastening inserting machines of 115 the type herein shown are not usually provided with work supports to support the work against the thrust of the fastening inserting operation, the work being held against such thrust by the hand of the operator, and in the illustrated construction, therefore, the principal functions of the work holder are to gage and guide the work 120 and to feed the work between the successive fastening inserting operations.

According to the present invention, the

machine is provided with an automatic mechanism that supports in position the shoe, so that the tacks are driven into the heel seat in a row that is substantially parallel with the contour of the edge of the heel seat. The automatic mechanism comprises a pair of cranks 2 and 4 mounted upon shafts 6 and 8 respectively that are rotatably mounted in a bracket 10 supported on the machine frame 12. Pivoted upon the crank pin 14 of the rearmost crank 4 is an extension 16 from a member 17 that carries a work clamp, presently to be described, and the crank pin 18 of the foremost crank passes through a slot 20 formed in said member. The cranks are geared so as to rotate in the same sense and each crank pin is adjustable toward and from the axis of the crank to which it appertains. Preferably the foremost crank has a somewhat higher angular velocity than that of its companion. Normally the crank pins are so adjusted on their respective cranks that the foremost crank has an effective length shorter than that of its companion, and the arrangement of the cranks and the member they support is such that rotation of the cranks moves said member and the work clamp and work in a curved path below the driver, so that tacks are inserted by the driver around a marginal portion of the heel seat to secure it to the innersole.

The cranks are rotated by a step-by-step movement in the same sense by mechanism that is described hereinafter and they rotate through a little more than half a revolution. In their initial positions the cranks extend to one side of, and slightly rearwardly of, the machine and during the first half of their movement, that is slightly more than a quarter of revolution, a forward and lateral movement is imparted to the work, the lateral component of the movement gradually increasing until it reaches a maximum when the cranks have completed the first half of the movement and are in alignment with one another. During this movement of the cranks, the slot 20 formed in the member aforesaid permits the member to slide on the pin 18 in the foremost crank, the slot 20 being disposed along the line that intersects both crank pins.

The first tack is inserted in the heel seat at a point near the shank of the shoe and the combined forward and lateral movement imparted to the shoe causes the heel seat to be moved beneath the driver along a path such that each nail is inserted at substantially the same distance from the edge of the heel seat as its companions. When the cranks are in alignment, as above described, the tack, or tacks nearest the heel end and the medial line of the shoe are inserted and

therewith the cranks complete the second half of their movement, thereby continuing the lateral movement of the shoe, but at the same time moving it backwardly so that tacks are inserted on the opposite side of the marginal edge of the heel seat. The work is held by a self-centering clamping device, comprising two levers 22, 24, pivoted to the member aforesaid and provided with intermeshing teeth that cause them to move in company, but in opposite directions. A spring 26 connecting said levers forces them into contact with the heel seat situated between them.

A rest for the end of the shoe comprises a counter-embracing band 28 secured to, or forming part of, a lug 30 that is detachably secured to the member 17 by a pair of leaf springs 32, 32 that enter notches formed in the lug. Each lever of the clamping device has a downwardly extending projection 34 that engages the counter-embracing band 28 and prevents the clamping levers closing in beyond a certain distance. The machine is provided with a driving mechanism for the cranks aforesaid, a reversing device for the driving mechanism which operates to set the mechanism, so that at the next operation of the machine the cranks shall move in the reverse direction and the locking device operates to lock the cranks against movement when a tack is being driven. These will now be described.

The driving mechanism for the cranks comprises a double-ended pawl 36 pivoted upon a pawl carrier 38 that is loosely mounted upon a shaft 40 journaled in the bracket 10 aforesaid. The pawl 36 is adapted to engage with one or the other of two ratchet wheels 42, 44 fast upon the shaft 40 above-mentioned. The teeth of each wheel are oppositely disposed with relation to the teeth of the other wheel so that the shaft can be rotated in either direction in accordance with the ratchet wheel with which the pawl is in engagement.

The pawl is yieldingly maintained in engagement with the teeth of one or the other of the ratchet wheels by a toggle device consisting of a ball-ended strut 46 of which one end is seated in a recess in an adjustable or other spring-pressed plunger 48 located in a socket 50 formed on the pawl-carrier while the other end of said strut is seated in a recess formed in a projection upon the pawl. The pawl-carrier is oscillated about its center by connections from the frame 52 that supports the strip carrier 54 in the machine to which the invention is herein shown as applied. For a more detailed description of the construction of this machine reference may be had to United States Letters Patent 125 to L. Goddu, No. 490,623, granted January

24, 1893. This frame is moved laterally during the operation of the machine, and such movement is herein utilized to oscillate the pawl-carrier 38. The connections between 5 the frame and carrier comprise an adjustable or other collar 56 on the rear end of the frame 52, and a ball-ended extension 58 on the carrier engaging a seating formed in the collar.

10 The shaft 40 that carries the ratchet wheels is operatively connected to the two shafts 6 and 8 of the cranks aforesaid by means of gear wheels 60 and 62 on the respective shafts 6 and 8, coupled by an intermediate 15 gear wheel 64 and a clutch or locking device between the gear 62 on the rearmost crank shaft and the shaft 40 of the ratchet wheels, it being understood that the shaft 8 of the rearmost crank is hollow and receives within 20 it the shaft 40 of the ratchet wheels. The clutch or locking device comprises two blocks 66, 68, adjustably supported upon the gear 62 on the rearmost crank shaft 8, and a casing 70 secured to or forming part of the 25 bracket 10 aforesaid.

The casing 70 surrounds the gear wheel 62 and the blocks on the latter are cut away to form clutch pockets 72, 74, in each of which is seated a roller 76, 78, that is acted upon 30 by a spring 80 which forces it into a narrow portion of the pocket and against the casing 70, and thereby locks the block and gear wheel against rotation. Each roller acts to 35 lock the gear wheel against rotation in a direction opposite to that against which its companion locks the gear wheel, so that the latter, as long as the rollers are acting, cannot be moved in either direction.

To unlock the gear wheel and cause it to be 40 rotated, there is a collar 82 secured to the shaft 40 of the ratchet wheels, which collar has a projection 84 that extends through a hole formed in the gear wheel 62. The end of said projection is situated between the 45 two clutch rollers 76, 78, so that rotation of the said shaft in one or the other direction causes the projection first to engage a clutch roller and move it into a wider part of the clutch pocket in which it is seated, thus unlocking the gear wheel and permitting it to 50 be rotated by the said projection which next engages a part of the wheel, preferably one end of the hole through which the projection extends.

55 With the above construction, the gear wheels, crank shafts, and work clamp are rigidly held against movement at all times, except just when the pawl is acting to impart movement to them, as it will be understood that during movement of the parts in any given direction one clutch roller is in a position to prevent reverse movement of the parts while immediately as the pawl begins

its idle stroke the companion roller is moved by its spring into the narrow part of its 65 clutch pocket and stops all movement of the parts in such given direction.

The reversing device hereinbefore referred to consists of two adjustable or other projections 86, 88, supported upon the hollow 70 shaft 8 of the rearmost crank. One or the other of these projections as the crank shaft is rotated, will be brought into the path of movement of a tail piece 90 on the double-ended pawl 36 as the latter is making its 75 return or idle stroke and will cause the pawl to be tipped about its pivot and bring its other end into engagement with the companion ratchet wheel. This occurs at the end of the operation of the machine upon 80 the heel seat of one shoe, so that the automatic mechanism will be set in readiness to deal with the next shoe which it will move in the same path as that in which it moved the first shoe, but in the reverse direction. 85

As the lateral component only of the movement of the shoe is reversed in direction it will be clear that the curved line of tacks inserted in the second shoe will correspond exactly with that inserted in the first shoe, 90 the order in which the tacks are inserted being, of course, immaterial. At the end of the operation of the machine upon the heel seat of the second shoe, the tail piece 90 of the pawl 36 will be engaged with the companion projection and the pawl will be returned to its original position as the movement of the third shoe along the same path and in the same direction in which the first shoe is moved. 95

It is to be noted that the projections 86, 88, act upon the tail piece 90 of the pawl during the return or idle stroke of the latter, and as has been pointed out hereinbefore the cranks and their appurtenances are rigidly locked against movement at this time. Accordingly, said projections which are supported on one of the crank shafts, will likewise be locked against movement, and therefore they will act in co-operation with the toggle device 46, 48, of the pawl with certainty and precision to tip the latter about its pivot. 100

As the machine herein described is sometimes employed to insert tacks in parts of the shoe other than the heel seat, it is desirable that said automatic mechanism be arranged to be removed from its operative position. Accordingly, the bracket 10 which supports the automatic mechanism is secured to a vertical shaft 92 that is journaled in bearings on the machine frame. The shaft is coupled to a knee lever 94 pivoted upon an extension 96 upon the machine frame, so that the bracket can be 115 moved by the knee lever into positions that 120

125

correspond to the operative and inoperative positions in said mechanism.

Preferably, means is provided for locking the bracket in its two extreme adjusted 5 positions, and to this end the connection between the knee lever and the vertical shaft is constructed as follows: To the lower end of the shaft is secured a socket 98 which receives a rod 100 that is pivoted to the end 10 of the knee lever 94. An adjustable or other spring-pressed plunger 102 carried on an extension from the socket has a V-shaped end that is adapted to engage a similarly shaped recess 104. The knee lever and rod 15 constitute a toggle joint, and when the automatic mechanism is in its operative or in its inoperative position the toggle is broken and the plunger, by engaging the V-shaped recess in the rod locks it and the mechanism 20 in said position. As the knee lever is moved by the operator to shift said mechanism from one adjusted position to the other, the rod 100 moves rearwardly in the socket until the toggle joint passes a central position 25 when a continued movement of the knee lever will cause the rod to reverse its movement until the plunger, which was forced out of the V-shaped recess by the rearward movement of the rod, is again in register 30 with and enters said recess to lock the mechanism in its new position.

It is to be understood that the ball-ended extension in the pawl carrier and the seating formed in the strip carrier frame are 35 shaped to permit them to be disengaged when the automatic mechanism is swung by the knee lever into its inoperative position.

In the operation of the machine, the crank pins 14 and 18 are adjusted to suit the shape 40 of the particular heel seat to be operated upon. The reversing projections 86, 88, for the double-ended pawl are adjusted also in accordance with the number of the tacks 45 that are to be inserted, and the position 50 which they shall occupy in the shoe and a suitable counter-balancing band 28 is applied to the clamping device. These adjustments having been made, if necessary, the operator places the shoe in the work clamping device and then starts the machine. Tacks are then driven by the driver into 55 the heel seat of the shoe, the shoe being held rigidly while the tacks are driven, and then again released so that it can be fed step-by-step by the mechanism hereinbefore described. At or about the time the last tack 60 is driven, the double-ended pawl 36 is tipped about its pivot as described and the machine which is now stopped is in readiness 65 to operate upon the heel seat of another shoe. If the operator wishes to insert tacks in parts of the sole other than the heel seat, he now removes the shoe from the work

clamping device and swings the knee lever 70 65 to move the automatic mechanism into its inoperative position. It is to be understood that the present invention is not to be construed as limited to the particular construction herein set forth, or in its application to tack driving machines, for the invention can be embodied in many other constructions or applied to machines other than tack driving machines without departing from the scope thereof.

The provision of automatic mechanism 75 for effecting various steps in the operations for which the illustrated embodiment of the invention is intended to be used such as would readily suggest itself to one skilled in the art upon reading the description of 80 the said operations is believed to be within the scope of this invention, and it is intended to cover broadly in the appended claims not only the illustrated construction but its obvious modifications.

Having described my invention, what I claim as new and desire to secure by Letters Patent of the United States is:—

1. A machine of the class described, having, in combination, a tool, a work holder 90 presenting a work receiving opening to the operator, means for automatically and positively effecting a relative feeding movement of said work holder and tool along a path corresponding substantially to the contour 95 of the work, constructed to constrain said work holder against presenting a different face of the work to the operator during the feeding movement, and means for reversing the operation of said aforementioned means 100 at the end of its operation upon one piece of work whereby the relative feeding movement of the tool and the work holder is reversed in direction for the succeeding piece of work.

2. A machine of the class described, having, in combination, an intermittently operating tool, and means for effecting positively between the operations of said tool a relative feeding movement of the work and 110 tool along a path corresponding substantially to the contour of the work, while presenting the same face of the work to the operator, said means being constructed and arranged to be automatically reversed at the 115 end of its feeding movement upon one piece of work whereby the succeeding piece of work is fed in a different direction past said tool.

3. A machine of the class described, having, in combination, an intermittently operated tool, intermittently operating work feeding means constructed and arranged to effect positively between the operations of said tool a feeding movement of the work 125 along a path corresponding substantially

to the contour of the work, while presenting the same face of the work to the operator, said feeding means being moreover so constructed and arranged as to be automatically 5 reversed at the end of the feeding movement upon one piece of work whereby the succeeding piece of work is fed in a different direction past said tool, and means for locking said feeding means to hold the work 10 stationary during the operation of the tool upon the work.

4. A machine of the class described, having, in combination, a tool, a self-centering work clamp opening toward the operator, 15 and means for automatically moving said work clamp past said tool along a path corresponding to the contour of the portion of the work embraced by said clamp, constructed to maintain said clamp in such 20 angular relation to the tool throughout the feeding movement that the opening in the clamp is constantly presented to the operator.

5. A machine of the class described, having, in combination, a tool, a self-centering work clamp constructed to adjust itself automatically to shoes of different sizes and presenting its work receiving opening toward the operator, and automatic means for 30 effecting positively a movement of said clamp past said tool along a path corresponding to the contour of the portion of the shoe embraced by the clamp, said means being constructed to maintain such an 35 angular relation between said clamp and said tool that the opening in said clamp is presented constantly to the operator.

6. A machine of the class described, having, in combination, a tool and a work holder 40 constructed to center the work as it is presented to said holder and to furnish an abutment against which the rear end of the work may be pressed constantly by the operator during the operation of the tool thereon, 45 and means for automatically and positively effecting a relative bodily movement of said holder and tool in such manner that the point of operation of the tool is transferred from one side of the work to the other along 50 a path corresponding to the contour of the work, and that the work receiving opening in the holder is presented constantly.

7. A machine of the class described, having, in combination, a tool and a work 55 holder constructed to engage the sides and an end of the work, and means for automatically and positively effecting relative bodily movements of said holder and tool in directions substantially normal to said 60 sides and said end of the work, said movements being so directed that the point of operation of the tool is transferred from one side of the work to the other along a

path corresponding to the contour of the work and that the work holder presents the 65 same face of the work to the operator throughout the relative movement of said holder and tool.

8. A machine of the class described, having, in combination, a tool and a work 70 holder constructed to furnish an abutment against which the rear end of the work may be pressed constantly by the operator during the operation of the tool thereon and means for automatically and positively 75 moving said work holder toward and away from the operator and in directions transverse to the direction of movement toward and away from the operator, said means being constructed to control the movements 80 of said holder in such manner that the point of operation of the tool is transferred from one side of the work to the other along a path corresponding to the contour of the work.

9. A machine of the class described, having, in combination, a tool and a work holder comprising a work clamp opening toward the operator, said holder being constructed to embrace the counter of a shoe 90 to position the sole of the shoe with respect to the tool and means for automatically and positively moving said work holder to cause the point of operation of said tool to be 95 transferred from one side of the work to the other along a path corresponding to the contour of the work, said means being constructed to cause said work holder to present the same face of the work to the operator throughout its movement.

10. A machine of the class described, having, in combination, fastening inserting mechanism and means for feeding the work beneath said inserting mechanism constructed to cause the work to be fed in such manner that a row of fastenings will be driven substantially parallel to its edge while presenting the same face of the work to the operator throughout the feeding movement, and means yieldingly engaging 110 the sides of the work for centering the work in said work feeding means.

11. A machine of the class described, having, in combination, a tool and mechanism for automatically feeding successive pieces 115 of work bodily in different directions along the same path beneath said tool, constructed and arranged to be moved bodily out of operative relation to said tool.

12. A machine of the class described, having, in combination, means for performing successive operations upon a shoe, and means for feeding the work bodily with relation to said operating means during each work feeding operation comprising a 120 work holder and work feeding mechanism 125

bodily movable into and out of operative relation to said operating means.

13. A machine of the class described having, in combination, an intermittently operated tool, mechanism operating automatically between the operations of said tool to carry the work bodily past said tool, and means for moving said mechanism bodily out of operative relation to said tool.

10 14. A machine of the class described having, in combination, an intermittently operated tool, mechanism operating automatically between the operations of said tool to carry the work upon which the tool

operates bodily past said tool, means for 15 moving said mechanism bodily out of operative relation to said tool, and means for locking said mechanism either in its operative or in its inoperative relation to said tool.

20 In testimony whereof I have signed my name to this specification in the presence of two subscribing witnesses.

Correction in Letters Patent No. 1,115,484.

It is hereby certified that in Letters Patent No. 1,115,484, granted November 3, 1914, upon the application of Arthur Bates, of Leicester, England, for an improvement in "Machines for Use in the Manufacture of Boots and Shoes," an error appears in the printed specification requiring correction as follows: Page 6, line 52, after the word "constantly" insert the words *to the operator*; and that the said Letters Patent should be read with this correction therein that the same may conform to the record of the case in the Patent Office.

Signed and sealed this 19th day of January, A. D., 1915.

[SEAL.]

R. F. WHITEHEAD,

Acting Commissioner of Patents.
